UNITED STATES PATENT OFFICE

JAMES F. KAVANAGH, OF CALUMET CITY, ILLINOIS, ASSIGNOR TO THE SUPERHEATER COMPANY, OF NEW YORK, N. Y.

BOILER

Application filed August 25, 1931. Serial No. 559,218.

This invention relates to baffles for boilers of the straight tube type having spaced banks of generating tubes.

In a common type of boiler there are horizontally inclined generating tubes arranged in upper and lower banks spaced apart sufficiently to provide room for a superheater between the banks. In many such installations a baffle is run along the upper surface 5 of the lower generating bank for a portion of the length of the tubes in such bank and then run upwardly to the tube of the upper bank, the superheater commonly being placed in the inter-bank space in the first pass so 10 formed. In such arrangements, one of the headers for the superheater is often placed in the second gas pass on the opposite side of the said baffle from the superheating elements, the ends of the elements extending 15 through the baffle to the header. This construction has required a special baffle structure in the space between the two generating banks, hereinafter referred to as the "interdeck" space. Such special construction has 20 given trouble at times from lack of tightness as well as from a high rate of depreciation.

It is an object of my invention to provide an improved baffle structure for the interdeck space of such superheater boilers.

The novel features of my invention will be pointed out in the appended claims. The invention itself, however, together with detail objects and advantages, will best be 35 understood from the following description of a superheater boiler which relates to an illustrative embodiment of my invention shown in the accompanying drawing. In said drawing

40 Fig. 1 is a vertical sectional view through an interdeck straight tube boiler.

Fig. 2 is a fragmentary view taken on the line 2—2 of Fig. 1 looking in the direction of the arrows.

45 Fig. 3 is a fragmentary view of a boiler similar to Fig. 1 but illustrating a modification.

Fig. 4 is a section on the line 4—4 of Fig. 3.

50 Referring to Figs. 1 and 2, 10 is a boiler of well-known type having a horizontally in-

clined upper bank of straight generating tubes 12, 12 and a lower bank of generating tubes one of which appears at 14, the remaining tubes of the lower bank being broken away. The banks having tubes 12 and 14 are 55 spaced vertically to provide an interdeck space 16. A baffle 18 extends vertically downward through the tubes 12 near their centre points and across the interdeck space 16 and thence laterally and downwardly 60 parallel to the upper surface of tube 14 to the lower end of the bank of which 14 is a part, so as to form one side of the first gas pass through the boiler. In order to protect the baffle 18 in the part below the tubes 12, 65 I provide a water cooled support for it including a row of tubes 20 running parallel to tubes 14 along their lower portion but turned upwardly near the centers of the tubes so as to contact with and support the 70 face of the baffle 18 on the side toward the first gas pass. At their lower ends, tubes 20 connect into the header 22 for the tubes 14 and at their upper ends tubes 20 connect into a horizontal header 24. The lower section 75 of the baffle 18 contacts with the lower portion of the header 24 and the upper section of the baffle 18 contacts with the top of the header. Header 24 therefore forms a portion of the baffle. The section of the baffle 80 which extends through the upper bank formed by the tubes 12 may be of ordinary construction, but a packing section 26 is preferably included between the upper surface of header 24 and the lower surface of the upper 85 section of the baffle. In order to provide for water circulation through the tubes 20, tubes 20 extend from the header 24 parallel to tubes 12 to the upper header 28.

When, as is usually the case, a superheater 30 is placed in the interdeck space 16 in the first gas pass, at least one of the headers 32 of the superheater is often placed in the second gas pass so that it is necessary to extend the tubes of the superheater through the baffle 18 to connect within the second pass. In the arrangement shown for this purpose, I have illustrated plates 34, 34 preferably of cast iron which lie on opposite sides of the vertical portions of the tubes 20 and which are 95 100

- clamped to these tubes by bolts and large nuts (not shown). The ends 30' of the superheater elements pass through notches, not shown, in the edges of plates 35 guided on plates 34, 5 the plates 35 being separated by vertical seams and having complementary notches along the separating seams forming openings through which the ends of the elements 30 pass. The openings in plates 34 are covered 10 by the notched plates 35 which are clamped to elements 30 but slideable vertically in guides on plates 34. The arrangement described whereby the ends 30' of elements 30 pass through baffle 18 without detracting from its 15 efficiency as a baffle forms no part of my invention and is not claimed herein, being disclosed and claimed in application, Ser. No. 431,783, filed Feb. 27, 1930, by Charles W. Gordon.
- 20 Referring to Figs. 3 and 4, the modification illustrated in these figures relates solely to the arrangement for connecting the ends of the tubes 20 and 20'. In the arrangement shown in Figs. 3 and 4, individual box headers 40, 40, 25 one between each tube 20 and its continuation 20', are substituted for the horizontal header 24.

It will be seen that the construction in accordance with my invention not only prolongs the life of the baffle by cooling it as well as making a tight construction, but also reduces the number of parts and provides greater flexibility than does the ordinary arrangement.

35 What I claim is:

1. A boiler having in combination a vertically spaced pair of banks of horizontally inclined generating tubes, a row of tubes extending along and crossing the space between said banks, a baffle structure extending in contact with said row from its lower end to a point near said upper bank and thence upwardly through the upper bank so as to separate the first gas pass from the second, said 40 tubes of the baffle supporting row of tubes having two portions, header means near the upper tube bank for connecting said portions, and said baffle having a packing section contacting with the upper face of said header 45 means.

2. A boiler having in combination a vertically spaced pair of banks of horizontally inclined generating tubes, a row of tubes extending along and crossing the space between said banks, a baffle structure extending in contact with said row from its lower end to a point near said upper bank and thence upwardly through the upper bank so as to separate the first gas pass from the second, said 55 row lying closely adjacent the upper surface of the lower of said banks for a considerable portion of the length of such row and closely adjacent the lower surface of the upper of said banks for another considerable portion 60 of the length of such row and having a sub-

stantially vertical portion intermediate said portions, and header means at the junction of said vertical portion with one of said other portions.

3. A boiler set forth in claim 2 and in which the header means lies at the upper end of the vertical portion of the row of tubes crossing the space between the banks, and the baffle has a packing section contacting with the upper 75 face of the header means.

JAMES F. KAVANAGH.
